CAPPING APPARATUS

Howard E. Gantzer, Kenmore, N. Y., assignor to
 Consolidated Packaging Machinery Corporation,
 Buffalo, N. Y., a corporation of New York

Application October 8, 1936, Serial No. 104,571

18 Claims. (Cl. 226—86)

The present invention relates to an improved cap applying chuck and capping machine for operating the same. The chuck comprises novel means to actuate a deforming annulus and cooperating members to apply deformable caps of the type comprising a protruding bead which is crimped and locked onto lugs or flanges of containers, and the machine comprises improvements in a known type of machine whereby the 5 aforesaid chuck may be substituted for other types of chucks.

The present application is a continuation in part of my copending application Serial No. 48,993, filed November 9, 1935. The machine in 15 which the chuck is preferably employed is preferably of the type disclosed and claimed in the patent to Robert N. Cundall No. 1,773,960, and my copending application Serial No. 683,432, filed August 3, 1933, which has matured into Patent 20 No. 2,076,631, dated April 13, 1937.

The basic principles of the present invention may be embodied in many forms in order that various sizes, shapes and types of deformable caps may be manipulated. One form of the present invention is designed with respect to a cap known to the trade as the "tailor-made" or "tailored" cap, comprising a cap which is partially rotated to position indentations of the cap beneath lugs on the container and is then deformed to fit the cap to the container, thereby frictionally locking the indentations beneath the lugs. One object of the present invention is to devise a chuck which will rotate the cap until the indentations are seated and will then apply 30 deforming pressure to clinch the cap in place, the chuck being so designed that individual variations in both the cap and the container do not alter the performance of the chuck.

An advantage of the present invention lies in 40 its simplicity and the relative simplicity of substituting the present chuck for others designed to accomplish other functions. A feature of the present invention lies in the adjustability of the various working parts and the ease of controlling 45 the pressures applied to the cap. A further feature of the invention lies in the relation of various parts with respect to one another whereby uniform results are achieved in spite of minor variations in the caps and containers.

Other objects and advantages of the present 50 invention will be realized from the following specification taken in connection with the accompanying drawings wherein like numerals refer to like parts throughout.

55 Referring to the drawings:

Fig. 1 discloses one form of the invention which may be used under certain circumstances, showing the chuck in open condition;

Fig. 2 is a quarter-section of the chuck of Fig. 1 showing the same in closed or operating condition;

Fig. 3 is a side view of the neck of a container provided with lugs designed to hold a tailor-made cap;

Fig. 4 is a view, partially in cross-section, of 10 a "tailor-made" cap;

Fig. 5 is a quarter-section of a modified form of the chuck, showing the same in open position;

Fig. 6 is a view in skeleton outline showing the chuck of Fig. 5 in closed position, Figs. 5 and 6 15 being juxtaposed to show the relative position of operating parts from the time the chuck jaws commence to close until the same are at their innermost positions;

Fig. 7 is a view in vertical cross-section of the 20 essential parts of a preferred form of capping machine having the chuck of Fig. 5 applied thereto and

Fig. 8 is a detailed view of a portion of a modified form of chuck which may be found desirable 25 under some circumstances.

Referring to Fig. 1 there is shown a chuck-supporting head 10 which is adapted to be connected to a spindle rotatably and slidably mounted in a capping machine in the manner of the 30 spindles illustrated and claimed in the patent to Robert N. Cundall #1,773,960, the spindle, machine and chuck being shown in operative connection in Fig. 7. The head 10 is provided with an enlarged disc-shaped flange 11 which guides a 35 relatively movable cylindrical member 12 provided with an overhanging flange 13 positioned above the flange 11. A washer 14 made of leather or other frictional material is mounted upon and fixed to flange 13, the rotation of head 10 40 transmitting rotation to the cylindrical member 12 when in contact therewith. The member 12 supports the operating parts of the chuck, which include an annular cam ring 15 rigidly fastened to member 12 and forming an extension thereof 45 and a cap-deforming annulus 16 rigidly fastened to cam ring 15 and spaced inwardly therefrom. The member 12, cam ring 15 and cap deforming annulus 16 form a relatively integral structure which always moves as a unit. A central plunger 17 is guided within annulus 16 and is provided with a guiding flange 18 at its upper end which slides relative to the inner surface of member 12. A spring 19, compressively mounted between an- 50 nulus 16 and flange 18, tends to keep flange 11 in 55

rotating contact with washer 14, a plurality of balls 20 placed on the top of flange 18 transmitting the thrust of the spring. A plurality of radial slots 21 are cut through the wall of annulus 16 and a plurality of rocking fingers 22 are mounted in the slots, each finger extending radially inward and outward from the annulus. The inner ends of the fingers are confined within an annular groove 23 in the lower end of plunger 17 and the outer end of each finger is confined within a groove 25 in each of a plurality of concentric outer members 26, the members 26 being slidably guided between the cam ring 15 and annulus 16. The lower end of each of the members 26 is provided with a recess 27 within which is confined an endless coil spring 28 which tends to keep the lower ends of said members in the relationship shown in Figs. 1 and 2. The lower end of each member 26 is also provided with an outer heel 29 and an inner toe 30, the heel designed to be confined within the cam ring 15 in order to center and rigidly back the members 26 when in operation and to pass below the annulus 16 in order that the members 26 may spread against the tension of spring 28 in order to pass beneath the flange of a cap and hold the same. The toes 30 constitute deforming portions which, together with the inwardly recessed lower face of annulus 16, fit the cap to the bottle by compressing the deformable bead thereon. The toes 30 and the annulus 16 therefore constitute relatively movable chuck jaws.

When the chuck is in the normal position illustrated in Fig. 1, spring 19 maintains the washer 14 in driving contact and maintains the heels 29 below the end of cam ring 15. In such position the chuck may be lowered onto a previously positioned cap, or onto a cap presented thereto by suitable cap-feeding mechanism (not shown), which it will engage by reason of the members 26 spreading until the fingers 30 pass below the bead 35 of the cap. The cap may now be lowered onto the neck of a container (if it has not been so placed previously) until the lower edge of the skirt 36 contacts the flange 37 of the container or until the top of the cap or the sealing plug 38 contacts the edge 39 of the container, the indentations 40 provided on the cap finding their way between the lugs 41 provided on the container. The toes 30 grip the cap with sufficient force to transmit rotation of head 10 to the cap until the indentations 40 strike the extensions 42 of the lugs 41, whereupon the chuck will slip relative to the rotating head 10, the frictional factors involved being such that slippage will occur. Continued downward pressure on the head 10 separates flanges 11 and 13 as shown in Fig. 2 and lowers the plunger 17, thereby compressing spring 19 and rocking fingers 22 when the lower surface of annulus 16 contacts the top of the cap. The upper surface of the bead 35 is depressed by the lower surface of the annulus and the sealing plug 38 is forced into the neck of the container to an extent determined by the strength of spring 19. The outer members 26 concentrically locate the cap by reason of the heels 29 being confined within the cam ring 15 and raise the indentations 40 against the lower surfaces of the lugs 41. As the plunger moves downward the rocking fingers 22 transmit upward movement to outer members 26 and the bead of the cap is deformed between the annulus and the toes 30.

Figs. 5 and 6 illustrate a modified form of chuck embodying features of great advantage.

The modified form seats the upper portion and top of the cap within the depression in the lower surface of the annulus at the same time that the cap is engaged by the toes of the outer members thus insuring accurate and reliable positioning of the cap within the chuck. Also in the modified form the chuck jaws are opened only to such an extent that the bead on the cap is loosely embraced and are closed only to an extent sufficient to deform the bead. Other features of the improved form will be apparent from the following description:

Rotation is imparted to the chuck by a head 10' comprising a driving flange 11' over which is positioned a cylindrical member 12' comprising an overhanging flange 13', a friction washer 14' being positioned between the said flanges. Cylindrical member 12' is fixed to an annular cam ring 15' constituting an extension of the member, the members 12' and 15' moving as a unit. A central plunger 17' is guided by and guides a deforming annulus 16' which is loosely mounted to slide in the space between cam ring 15' and plunger 17'. A compression spring 19' is mounted between cam ring 15' and a flange 18' at the upper end of plunger 17'. A thrust bearing 20' is positioned between flanges 11' and 18' in order to transmit downward thrust from head 10'. A plurality of radial slots 21' are cut through the wall of annulus 16' and a plurality of rocking fingers 22' are mounted therein with their ends extending radially therefrom. The inner ends of fingers 22' are positioned within a groove 23' in the lower end of plunger 17', a pin 52 insuring rotation of the fingers with the plunger, and the outer end of each of the fingers is positioned within a groove 25' in each of a plurality of concentric outer members 26'. The concentric outer members are mounted to slide vertically between the annulus 16' and the inner surface of cam ring 15' and are provided with a retaining groove 27' within which is mounted an endless coil spring 28' tending to keep the members in inward position. The lower ends of members 26' are provided with heels 29' which cooperate with cam ring 15' to center and rigidly back the outer members and with toes 30' adapted to engage beneath the bead of a cap presented thereto.

Annulus 16' is pressed downwardly by a coil spring 50 positioned between the top of the annulus and the flange 18', the downward movement of the annulus being limited by engagement of the rocking fingers with the lower surface of the groove 23'. The fingers 22' and the slots 21' are shaped rigidly to lock the parts in definite position, the compression of spring 50 causing the parts to assume the relationship shown in Fig. 5. Upon downward movement of the chuck (and rotation thereof as previously described to seat the sealing plug 38 against the upper edge 39 of a container) spring 50 will be compressed while compressing the sealing plug 38 without there being any effect upon spring 19'. Since members 12' and 15', through the frictional contact of spring 19' and other parts, transmit rotation to the chuck jaws it can be seen that a very light resistance to rotation will cause the chuck to stop rotating in spite of the fact that the cylindrical member 12' and cam ring 15' continue to move downward as a unit with head 10' and plunger 17' until the inner portion of cam ring 15' strikes the ledge 51 on annulus 16'. Up to this point the compressive force applied to sealing plug 38 has been that of spring 50 75

which may be sufficiently light to permit proper seating of the depressions 40 beneath lugs 41; but at this point the compressive force of spring 19' is added. The compressive force of spring 19' is so chosen that its force, together with that of spring 50, is such that the container will be properly sealed to prevent leakage. Continued downward movement of head 10' now causes the rocking of fingers 22' and therefore the raising of members 26' which have previously been surrounded and centered by the cam ring 15'. It is to be noted that the groove 23' is of sufficient width so that the upper surface of the groove strikes the fingers 22' at about the instant that cam ring 15' strikes the ledge 51. Fig. 6 shows the relative position of all of the sliding parts at the instant of extreme deforming movement of the chuck jaws, showing that the annulus 16' remains stationary, except for movement incident to the compression of the sealing plug, from the instant the container commences to resist downward movement and also that the movement of members 26' is limited to that sufficient to impart the proper squeezing force firmly to lock 25 the cap to the container.

Upward movement of head 10' results, first, in expansion of spring 19', thereby raising plunger 17' until the lower surface of groove 23' strikes the rocking fingers 22'. Continued movement causes the friction member 14' to engage flange 13' and movement of plunger 17' and cam ring 15' as a unit together with simultaneous opening of the jaws. Since the heels 29' pass below the confining limits of cam ring 15' the members 26' may open sufficiently to permit the chuck to release the capped container. It can be seen that the present form does not tend to raise the container and existing forms of capping machines may be used without the provision of container-elevating mechanism.

Fig. 7 shows the chuck of Figs. 5 and 6 in use upon a preferred existing form of machine. The machine comprises a fixed non-rotating post 60 about which a table 61 is mounted to rotate. Spaced discs 62 and 63 are connected to rotate with table 61 by means which are not shown, reference being made to Letters Patent No. 1,773,960, previously mentioned, for a disclosure of such parts. Vertical rods 64 extending between table 61 and disc 62 carry clamping arms 65 and crank arms 66, the latter being provided with cam followers 67 which engage a cam track 68 provided on the lower surface of a fixed driving gear 69 fastened to post 60 by a set screw 70. The gear 69 is provided with vertical teeth 75 of considerable width which are engaged by spur gears 76 fixed to spindles 77 vertically guided in bearings 78 and 79 provided in discs 62 and 63, respectively. The spindles are provided with elevating mechanism comprising horizontal rollers 80 maintained in radial alignment with post 60 by guides disclosed in the aforementioned patent. The rollers 80 ride upon a ring cam 81 fixed to the upper surface of gear 69 and elevate or lower the spindles as shown, the relative widths of gears 69 and 76 causing contact to be maintained therebetween whereby the spindles are continuously rotated about their axes as they are rotated bodily about the post 60. At the operative position of the chuck the spindles are lowered to such a position that the sealing plug of a cap rests upon the upper edge of a container. In order resiliently to lower the spindle to proper position a depressing cam 85 is provided, the same being mounted upon an arm 86 pivotally

mounted on a collar 87 fixed to gear 69 and provided with a limiting abutment 87 and a depressing spring 88 adjustably compressed between the surface of the arm and the head of an adjusting bolt 89 as disclosed in the aforesaid Letters Patent No. 2,076,631. As the chuck rotates from its open position at the right of Fig. 7 it is partially lowered to pick up a cap presented thereto by mechanism of the usual type (not shown) and is then lowered into operating position as shown at the left of Fig. 7, the container having been positioned on table 61 by mechanism (not shown) and clamped by a clamping arm 65 in substantially vertical alignment with the chuck. The containers are ejected from the machine as the table and rotating parts pass from the left to the right of Fig. 7.

As shown in said Patent No. 1,773,960, an ejecting plunger 100 may be mounted in a bore of spindle 77 and provided with an enlarged head 101 confining a light compression spring 122 between the head and the fitting 91. At the uppermost position of the spindle the head 101 strikes an adjustable abutment 102 carried by a ring 103 mounted upon disc 63 which causes compression 25 of spring 122 and projection of the ejecting plunger beneath the lower surface of the annulus 16' to assure the removal of caps which failed to become seated upon a container.

Fig. 8 shows a feature which may be found of value in large chucks comprising a series of springs 110 seated in bores in the toes 30 and the lower surface of the annulus 16. These springs are designed to be loosely held until the chuck is in squeezing or closed position and may 35 be so proportioned as to tend to overcome frictional resistance of the jaws against separation after operating.

Modifications in arrangement and detail of the present invention may be devised by those skilled in the art, and the true scope of my invention is to be determined by the following claims.

I claim:

1. A capping chuck adapted to apply deformable caps to containers comprising a cap-deforming annulus, a plurality of rocking fingers mounted upon said annulus and projecting radially therefrom, a central plunger movable relative to said annulus and having such operative engagement with the inner ends of said fingers as to rock said fingers in either direction, a plurality of outer cap-deforming members having operative engagement with the outer ends of said fingers whereby said members may be moved toward and away from said annulus by said fingers, and a cam ring surrounding said members within which said members are guided upon movement thereof.

2. A capping chuck adapted to apply deformable caps to containers comprising a cap-deforming annulus, a plurality of rocking fingers mounted upon said annulus and projecting radially therefrom, a central plunger having operative engagement with the inner ends of said fingers and movable relative to said annulus whereby to rock said fingers, a plurality of outer cap-deforming members having operative engagement with the outer ends of said fingers whereby said members are drawn toward said annulus by said fingers, and a cam ring attached to said annulus and surrounding said members, said members being movably guided between said annulus and said cam ring whereby said cam ring rigidly backs and centers said outer members upon relative movement thereof toward said annulus.

3. A capping chuck adapted to apply deformable caps to containers comprising a cap-deforming annulus, a plurality of rocking fingers mounted upon said annulus and projecting radially therefrom, a central plunger having operative engagement with the inner ends of said fingers and movable relative to said annulus whereby to rock said fingers, a plurality of outer cap-deforming members having operative engagement with the outer ends of said fingers whereby said members are drawn toward said annulus by said fingers, a cam ring surrounding said members and adapted rigidly to back and center said members upon relative movement thereof toward said annulus, and resilient means yieldably retaining said members in position upon movement of said members from engagement with said cam ring.

4. A capping chuck adapted to apply deformable caps to containers comprising a cap-deforming annulus, a plurality of rocking fingers mounted upon said annulus and projecting radially therefrom, a central plunger having operative engagement with the inner ends of said fingers and movable relative to said annulus whereby to rock said fingers, a plurality of outer cap-deforming members having operative engagement with the outer ends of said fingers whereby said members are drawn toward said annulus by said fingers, a cam ring surrounding said members and adapted rigidly to back and center said members upon relative movement thereof toward said annulus, and resilient means yieldably retaining said members in position upon movement of said members from engagement with said cam ring, said members being provided with inwardly projecting toes adapted to spread against the tension of said resilient means and to engage the flange of a cap when in projected position.

5. A capping chuck adapted to apply deformable caps to containers comprising a cap-deforming annulus, a plurality of rocking fingers mounted upon said annulus and projecting radially therefrom, a central plunger having operative engagement with the inner ends of said fingers and movable relative to said annulus whereby to rock said fingers, a plurality of outer cap-deforming members having operative engagement with the outer ends of said fingers whereby said members are drawn toward said annulus by said fingers, a cam ring surrounding said members and adapted rigidly to back and center said members upon relative movement thereof toward said annulus, resilient means yieldably retaining said members in position upon movement of said members from engagement with said cam ring, said members being provided with inwardly projecting toes adapted to spread against the tension of said resilient means and to engage the flange of a cap when in projected position and being also provided with projecting heels adapted to engage the inner surface of said cam ring upon retraction of said members.

6. A capping chuck adapted to apply deformable caps to containers comprising a cap-deforming annulus, a plurality of rocking fingers mounted upon said annulus and projecting radially therefrom, a central plunger having operative engagement with the inner ends of said fingers and movable relative to said annulus whereby to rock said fingers, a plurality of outer cap-deforming members having operative engagement with the outer ends of said fingers whereby said members are drawn toward said annulus by said fingers, a cam ring surrounding said members and adapted rigidly to back and

center said members upon relative movement thereof toward said annulus, resilient means yieldably retaining said members in position upon movement of said members from engagement with said cam ring, said members being provided with inwardly projecting toes adapted to spread against the tension of said resilient means and to engage the flange of a cap when in projected position and being also provided with projecting heels adapted to engage the inner surface of said cam ring upon retraction of said members, and a spring compressively mounted between said annulus and said plunger and yieldably resisting the rocking of said fingers.

7. A capping chuck adapted to apply deformable caps to containers comprising a cap-deforming annulus, a plurality of rocking fingers mounted upon said annulus and projecting radially therefrom, a central plunger having operative engagement with the inner ends of said fingers and movable relative to said annulus whereby to rock said fingers, a plurality of outer cap-deforming members having operative engagement with the outer ends of said fingers whereby said members are drawn toward said annulus by said fingers, a cam ring surrounding said members and adapted rigidly to back and center said members upon relative movement thereof toward said annulus, resilient means yieldably retaining said members in position upon movement of said members from engagement with said cam ring, said members being provided with inwardly projecting toes adapted to spread against the tension of said resilient means and to engage the flange of a cap when in projected position and being also provided with projecting heels adapted to engage the inner surface of said cam ring upon retraction of said members, a spring compressively mounted between said annulus and said plunger and yieldably resisting the rocking of said fingers, a rotatable chuck supporting head adapted to move said plunger relative to said annulus and to compress said spring, and means to cause rotation of said cam ring with said head when said spring is extended.

8. A capping chuck adapted to apply deformable caps to containers, comprising a cap-deforming annulus, a plurality of rocking fingers mounted upon said annulus and projecting radially therefrom, a central plunger having operative engagement with the inner ends of said fingers and movable relative to said annulus whereby to rock said fingers, the connection between said plunger and said fingers comprising a groove in said plunger within which said fingers extend, said groove being of greater width than said fingers whereby some of the motion of said plunger is lost, and a plurality of outer cap-deforming members having operative engagement with the outer ends of said fingers whereby said members are drawn toward said annulus by said fingers.

9. A capping chuck adapted to apply deformable caps to containers comprising a cap-deforming annulus, a plurality of rocking fingers mounted upon said annulus and projecting radially therefrom, a central plunger having operative engagement with the inner ends of said fingers and movable relative to said annulus whereby to rock said fingers, the connection between said plunger and said fingers comprising a groove in said plunger within which said fingers extend, said groove being of greater width than said fingers whereby some of the motion of said plunger is lost, a plurality of outer cap-deforming members having operative engagement with the

outer ends of said fingers whereby said members are drawn toward said annulus by said fingers, and a cam ring surrounding said members within which said members are guided upon movement thereof.

to spread against the tension of said resilient means and to engage the flange of a cap when in projected position.

13. A capping chuck adapted to apply deformable caps to containers comprising a cap-deforming annulus, a plurality of rocking fingers mounted upon said annulus and projecting radially therefrom, a central plunger having operative engagement with the inner ends of said fingers and movable relative to said annulus whereby to rock said fingers, the connection between said plunger and said fingers comprising a groove in said plunger within which said fingers extend, said groove being of greater width than said fingers whereby some of the motion of said plunger is lost, a plurality of outer cap-deforming members having operative engagement with the outer ends of said fingers whereby said members are drawn toward said annulus by said fingers, and a cam ring movable axially of said annulus and surrounding said members and adapted rigidly to back and center said members upon relative movement thereof toward said annulus, resilient means yieldably retaining said members in position upon movement of said members from engagement with said cam ring, said outer members being provided with inwardly projecting toes adapted to spread against the tension of said resilient means and to engage the flange of a cap when in projected position and being also provided with projecting heels adapted to engage the inner surface of said cam ring upon retraction of said members.

30 11. A capping chuck adapted to apply deformable caps to containers comprising a cap-deforming annulus, a plurality of rocking fingers mounted upon said annulus and projecting radially therefrom, a central plunger having operative engagement with the inner ends of said fingers
35 and movable relative to said annulus whereby to rock said fingers, the connection between said plunger and said fingers comprising a groove in said plunger within which said fingers extend, said groove being of greater width than said fingers whereby some of the motion of said plunger is lost, a plurality of outer cap-deforming members having operative engagement with the outer ends of said fingers whereby said members are drawn toward said annulus by said fingers, a cam
40 ring movable axially of said annulus and surrounding said members and adapted rigidly to back and center said members upon relative movement thereof toward said annulus, and resilient means yieldably retaining said members in position upon movement of said members from engagement with said cam ring.

45

50

14. A capping chuck adapted to apply deformable caps to containers comprising a cap-deforming annulus, a plurality of rocking fingers mounted upon said annulus and projecting radially therefrom, a central plunger having operative engagement with the inner ends of said fingers and movable relative to said annulus whereby to rock said fingers, the connection between said plunger and said fingers comprising a groove in said plunger within which said fingers extend, said groove being of greater width than said fingers whereby some of the motion of said plunger is lost, a plurality of outer cap-deforming members having operative engagement with the outer ends of said fingers whereby said members are drawn toward said annulus by said fingers, a cam ring movable axially of said annulus and surrounding said members and adapted rigidly to back and center said members upon movement relative thereof toward said annulus, resilient means yieldably retaining said members in position upon movement of said members from engagement with said cam ring, said outer members being provided with inwardly projecting toes adapted to spread against the tension of said resilient means and to engage the flange of a cap when in projected position and being also provided with projecting heels adapted to engage the inner surface of said cam ring upon retraction of said members, and a spring compressively mounted between said cam ring and said plunger and yieldably resisting relative movement of said cam ring and said plunger.

55 12. A capping chuck adapted to apply deformable caps to containers comprising a cap-deforming annulus, a plurality of rocking fingers mounted upon said annulus and projecting radially therefrom, a central plunger having operative engagement with the inner ends of said fingers and movable relative to said annulus whereby to rock said fingers, the connection between said plunger and said fingers comprising a groove in said plunger within which said fingers extend, said groove being of greater width than said fingers whereby some of the motion of said plunger is lost, a plurality of outer cap-deforming members having operative engagement with the outer ends of said fingers whereby said members are drawn toward said annulus by said fingers, a cam ring movable axially of said annulus and surrounding said members and adapted rigidly to back and center said members upon relative movement thereof toward said annulus, and resilient means yieldably retaining said members in position upon movement of said members from engagement with said cam ring, said outer members being 60 65 70 75 provided with inwardly projecting toes adapted

15. A capping chuck adapted to apply deformable caps to containers comprising a cap-deforming annulus, a plurality of rocking fingers mounted upon said annulus and projecting radially therefrom, a central plunger having operative engagement with the inner ends of said fingers and movable relative to said annulus whereby to rock said fingers, the connection between said plunger and said fingers comprising

a groove in said plunger within which said fingers extend, said groove being of greater width than said fingers whereby some of the motion of said plunger is lost, a plurality of outer cap-deforming members having operative engagement with the outer ends of said fingers whereby said members are drawn toward said annulus by said fingers, a cam ring movable axially of said annulus and surrounding said members and adapted rigidly to back and center said members upon relative movement thereof toward said members, resilient means yieldably retaining said members in position upon movement of said members from engagement with said cam ring, said outer members being provided with inwardly projecting toes adapted to spread against the tension of said resilient means and to engage the flange of a cap when in projected position and being also provided with projecting heels adapted to engage the inner surface of said cam ring upon retraction of said members, a spring compressively mounted between said cam ring and said plunger and yieldably resisting relative movement of said cam ring and said plunger, a rotatable chuck supporting head adapted to move said plunger relative to said annulus and to compress said spring, and friction means to cause rotation of said cam ring with said head when said spring is extended.

16. A capping chuck adapted to apply deformable caps to containers comprising a cap-deforming annulus, a plurality of rocking fingers mounted upon said annulus and projecting radially therefrom, a central plunger having operative engagement with the inner ends of said fingers and movable relative to said annulus whereby to rock said fingers, the connection between said plunger and said fingers comprising a groove in said plunger within which said fingers extend, said groove being of greater width than said fingers whereby some of the motion of said plunger is lost, a plurality of outer cap-deforming members having operative engagement with the outer ends of said fingers whereby said members are drawn toward said annulus by said fingers, a cam ring movable axially of said annulus and surrounding said members and adapted rigidly to back and center said members upon relative movement thereof toward said members, resilient means yieldably retaining said members in position upon movement of said members from engagement with said cam ring, said outer members being provided with inwardly projecting toes adapted to spread against the tension of said resilient means and to engage the flange of a cap when in projected position and being also pro-

vided with projecting heels adapted to engage the inner surface of said cam ring upon retraction of said members, a first spring compressively mounted between said cam ring and said plunger and yieldably resisting relative movement of said cam ring and said plunger, a rotatable chuck supporting head adapted to move said plunger relative to said annulus and to compress said spring, friction means to cause rotation of said cam ring with said head when said spring is extended, and a second spring compressively mounted between said annulus and said plunger and yieldably resisting the rocking of said fingers until said first spring commences to be compressed.

17. A capping machine adapted to apply a closure having a skirt provided with a protruding, compressible annular flange and locking means thereon, to the open end of a container provided with a lug adjacent its open end with which said locking means is adapted to engage when said flange is compressed, comprising a spindle, a chuck supported thereby, means to raise and lower said spindle and chuck with respect to a container positioned therebeneath, means to rotate said spindle about its axis during vertical movement thereof, said chuck including a clutch member adapted to disengage from said spindle when the closure is positioned on the container and further movement thereof is resisted by the container, and means within the chuck to squeeze the sides of the closure flange toward each other during further downward movement of the spindle.

18. A capping machine adapted to apply a closure having a skirt provided with a protruding, compressible annular flange and locking means thereon, to the open end of a container provided with a lug adjacent its open end with which said locking means is adapted to engage when said flange is compressed, comprising a spindle, a chuck supported thereby, means to raise and lower said spindle and chuck with respect to a container positioned therebeneath, means to rotate said spindle about its axis during vertical movement thereof, said chuck including a clutch member adapted to disengage from said spindle when the closure is positioned on the container and further movement thereof is resisted by the container, means within the chuck to squeeze the sides of the closure flange toward each other during further downward movement of the spindle, and means to vary the compressive force applied to the closure flange.

HOWARD E. GANTZER.
